UNITED STATES PATENT OFFICE.

OSCAR S. SWANSON, OF JAMESTOWN, NEW YORK.

LAMP-SOCKET CONSTRUCTION.

1,336,395.

Specification of Letters Patent.

Patented Apr. 6, 1920.

Application filed December 10, 1918. Serial No. 266,093.

To all whom it may concern:

Be it known that I, OSCAR S. SWANSON, a citizen of the United States, residing at Jamestown, in the county of Chautauqua 5 and State of New York, have invented new and useful Improvements in Lamp-Socket Constructions, of which the following is a specification.

My present invention pertains to lamp 10 socket constructions, and consists in the peculiar and advantageous features of construction in the cap of the socket, as hereinafter described and definitely claimed.

In the accompanying drawings, hereby 15 made a part hereof:

Figure 1 is an elevation of a socket constructed in accordance with my invention.

Fig. 2 is a diametrical section of the cap comprised in said socket.

Fig. 3 is an enlarged diametrical section of the metallic portion of said cap.

Fig. 4 is a diametrical section of a form of cap designed to receive and be connected to a conduit.

Fig. 5 is a diametrical section of said cap, taken in a plane at right angles to Fig. 4.

Fig. 6 is a side elevation of another modified form of cap.

Fig. 7 is an enlarged diametrical section 30 of said form.

Fig. 8 is a detail plan view of the neck of the last-named cap.

Referring by numerals to the said drawings, and more particularly to Figs. 1 to 35 thereof, 1 indicates the shell body of a lamp socket construction, and 2 indicates my novel cap. The said cap 2 comprises a metallic portion 3, best shown in Fig. 3, and which may be connected with the shell body 1 in 40 any approved manner without affecting my invention. The said metallic portion 3 is provided with an opening 4 and with spaced lugs 5 and 6, which extend upwardly and downwardly, respectively, from the wall of 45 the said opening. These lugs 5 and 6 are designed to be embedded in an insulating annulus 7, which rests in the said opening 4, as shown in Figs. 2, 4 and 5, and manifestly, by virtue of the said arrangement, 50 the metallic portion 3 and the annulus 7 are strongly connected of themselves and at the same time the metallic portion 3 is adequately and permanently insulated from any conductive element that may be disposed in the interior of the insulating an-

nulus. Manifestly the annulus 7 may be molded on the metallic portion 3 to receive the lugs 5 and 6.

In the form shown in Figs. 1, 2 and 3, the insulating annulus is designed for the reception of wires; and it will be observed by particular reference to Fig. 2 that the said annulus has a rounded flange 8 at its inner end between which and the adjacent portion of the metallic element 3 a space 9 is afforded. The said space 9 serves for the reception of an insulating annulus 10, which rests against the inner side of the metallic element 3. The opening in the said annulus 10 is of a less diameter than the flange 8, 60 and from this it follows that in positioning the annulus 10 in the metallic element 3 it is necessary to crowd said annulus over the flange 8 until the under edge portion of the annulus is disposed in the space 9, when 65 the annulus will manifestly be strongly held between the flange 8 and the metallic element 3 without the assistance of extraneous means.

The embodiment shown in Figs. 4 and 5 is similar to that shown in Figs. 1, 2 and 3, as regards the metallic portion or element 3, the insulating annulus 10, and the manner of connecting the metallic element 3 to the insulating annulus 7^a, as well as the manner of securing the insulating annulus 10 between the flange 8^a of the annulus 7^a and the adjacent portion of the metallic element 3. The insulating annulus 7^a of Figs. 4 and 5 is of larger interior diameter than the annulus 7 and is provided with a bushing 11 for the thread engagement of a conduit (not shown). The said bushing 11 is threaded interiorly and exteriorly and is retained in position in the insulating annulus 7^a by the flanges 12 and 13 at the upper and lower 85 ends of the bushing 11. At 14 the bushing 7^a is provided with a screw, which has for its purpose to fix the cap to a conduit (not shown). The said screw 14 is threaded in a radial bushing 15, and the said bushing 15 is disposed in the annular neck or annulus 7^a and has its inner end interlocked by a flange 16 on said end with a flange 17, provided on an annular countersink 18 that is 90 carried by and extends outwardly from the major portion of the bushing 11. The said countersink 18 is disposed in the substance of the annulus 7^a and is provided in order to preclude any interference between the 105

inner end of the bushing 15 and the conduit (not shown) incidental to the turning of the said conduit into the bushing 11. In this connection, it will be noticed that precedent 5 to the securing of the conduit into the bushing 11, the screw 14 may be turned outwardly until its inner end rests in the countersink 18 and beyond the circumference of the major portion of the bushing 11, and 10 hence there is no liability of the screw interfering with the turning of the conduit into the bushing.

In the modification shown in Figs. 6, 7 and 8, the metallic element 3^a and the insulating annulus 10^a, and the flange 8^b at 15 the inner end of the insulating annulus 7^b are relatively arranged in the manner before specifically described and for the purpose hereinbefore ascribed to said arrangement. It will be noticed, however, in the last-named embodiment that the metallic element 3^a is provided with a collar flange 20, in which are four (more or less) radial 20 openings 21; also that the insulating annulus 7^b is provided with say three radial 25 projections 7^c, which are disposed in three of the openings 21 with a view to holding the annulus in and strongly connecting the same to the metallic element. The remaining 30 aperture 21 in the collar flange 20 serves for the reception of a lateral internally threaded sleeve 22 on a bushing 11^c that is disposed in the annulus 7^b; the said lateral sleeve 22 serving for the reception and engagement 35 of a screw 23 through the medium of which the cap may be fixed upon a conduit or the like. The bushing 11^c is preferably machined, and is threaded at its inner side and smooth at its outer side. Therefore, in order 40 to contribute to the strength of the connection between the said bushing and the annulus 7^b, I prefer to crimp the end portions of the bushing 11^c over the opposed ends of the annulus 7^b, as will be readily understood by comparison of Figs. 7 and 8.

It will be apparent from the foregoing that my improved lamp socket construction is at once simple and inexpensive, susceptible of easy production without the employment 50 of expensive machinery, and is well adapted to withstand the usage to which the lamp socket constructions and particularly the caps thereof are ordinarily subjected.

As will be appreciated from the foregoing, 55 an important characteristic of my invention resides in the fact that there is absolutely no electrical connection between the metallic

element that carries the insulating annulus, and the bushing disposed within the insulating annulus.

Having described my invention, what I claim and desire to secure by Letters-Patent, is:—

1. A cap for use in lamp socket constructions comprising a metallic element having an opening and also having lugs extending upwardly and downwardly from the wall of the aperture, an annulus of insulating material arranged in said opening of the metallic element and receiving said lugs and having a rounded flange below the opening between which and the adjacent portion of the metallic element a space is afforded, and an annulus of insulating material arranged in the metallic element and having its aperture of less diameter than the greatest diameter of the flange on the first-named annulus. 70

2. A cap for use in lamp socket constructions, comprising a metallic member having an aperture and also having lugs extending upwardly and downwardly from the wall of the aperture, and an insulating annulus arranged in said aperture and extending at opposite sides of the same, and receiving the 75 said lugs of the metallic element. 80

3. A cap for use in lamp socket constructions, comprising a metallic element, an insulating annulus held to said element, a metallic threaded bushing disposed in the annulus and having a lateral countersink 90 extending outwardly in the annulus and provided with a flange, an internally threaded sleeve disposed in the annulus and having at its inner end a flange interlocked with that of the countersink, and a set 95 screw disposed in the said sleeve. 85

4. A cap for use in lamp socket constructions, comprising a metallic element having an aperture and a collar flange surrounding the aperture and also having radially disposed apertures in said collar flange, an insulating annulus disposed within the collar flange and having radial projections disposed in some of the apertures thereof, an internally threaded bushing arranged 100 and held against endwise movement in the insulating annulus and having an outwardly extending internally threaded sleeve disposed in the remaining radial aperture of the collar flange, and a set screw bearing in 110 the said sleeve. 105

In testimony whereof I affix my signature.

OSCAR S. SWANSON.
